United States Patent

Des. 237,697
Patented Nov. 18, 1975

237,697

TOY TRACTOR

Keith E. Brightbill, Nashville, Tenn., assignor to The
Murray Ohio Manufacturing Company, Brentwood,
Tenn.

Filed Nov. 13, 1973, Ser. No. 415,390

Term of patent 14 years

Int. Cl. D12—11

U.S. Cl. D12—113

Fig. 2

Fig. 3

Fig. 4

Fig. 5

Fig. 6

FIG. 1 is a perspective view of a toy tractor showing my new design;

FIG. 2 is a perspective view from the side opposite to that shown in FIG. 1;

FIG. 3 is a top plan view thereof;

FIG. 4 is a front perspective view thereof;

FIG. 5 is a rear perspective view thereof; and

FIG. 6 is a perspective view of a second embodiment thereof.

I claim:

The ornamental design for a toy tractor, substantially as shown.
